CABINET WRINGER

Original Filed Feb. 28, 1921 3 Sheets-Sheet 3

UNITED STATES PATENT OFFICE.

JOHN J. DOSSETT AND EDWIN E. GREAVES, OF SYRACUSE, NEW YORK, ASSIGNEES, BY MESNE ASSIGNMENTS, TO WESTINGHOUSE ELECTRIC & MANUFACTURING COMPANY, A CORPORATION OF PENNSYLVANIA.

CABINET WRINGER.

Original application filed February 28, 1921, Serial No. 448,459. Divided and this application filed June 30, 1921. Serial No. 481,485.

This invention relates to cabinet wringers and has for its object a particularly simple, efficient and compact arrangement of the wringer, and driving mechanism therefor by which the wringer can be readily mounted and demounted, and placed within the cabinet of the machine or alongside the tub when the machine is not in use.

The invention consists in the novel features and in the combinations and constructions hereinafter set forth and claimed.

In describing this invention, reference is had to the accompanying drawings in which like characters designate corresponding parts in all the views.

Figure 1 is an elevation, partly broken away and partly in section, of one form of washing machine embodying our wringer construction.

Figure 2 is a plan view partly broken away.

Figure 3 is a fragmentary elevation showing the wringer in elevated position.

This washing machine comprises a tub 1 which is enclosed in a suitable frame or cabinet 2, washing mechanism as a pounder 3 located in the tub 1 and actuating mechanism 4 for the movable parts of the washing machine, this mechanism being enclosed in a suitable housing 5 here shown as located below the tub. 6 designates a motor for driving the mechanism 4 and the wringer mechanism.

The foregoing parts form no part of this invention and for a full description, reference is had to our Patent 1,590,729, dated June 27, 1926, of which this is a division.

This invention comprises a wringer, and driving mechanism for the movable parts thereof located at one side of the tub, the wringer being shiftable relatively to the tub from a position below the top of the tub into a position above the same, and vice versa, out of and into the cabinet.

7 designates the wringer as a whole which is provided with a supporting bracket 8 at one end thereof, the wringer and the bracket

being mounted to move from a position below the top of the tub into a position above the tub from the position shown in Fig. 1 to that shown in Fig. 3. As here shown, the wringer is mounted to move vertically rectilinearly and the bracket 8 is provided with a tubular extension 9, which slides in a suitable passage 10 formed in a fixed bracket 11a preferably carried by the cabinet 2 at one side of the tub.

The wringer further includes movable parts, as rolls 11, 11a, having suitable compression means. The driving mechanism for the rolls includes a shaft 12 which is an extension of the axle of one of the rolls, the shaft 12 being journaled in the bracket 8, and gears 13 and 14 mounted on the shaft 12 within the bracket. It includes also a gear 15 mounted on a vertical shaft 16 extending lengthwise of the bracket, the gear 15 meshing with the gears 13, 14 on opposite sides of its axis, and a clutch 17 on the shaft 12, shiftable by means of a handle 18 to connect either of the gears 13, 14 and the shaft 12. The driving mechanism includes also a vertical shaft 19 below the bracket 8 with which the shaft 16 telescopes, the lower end of the shaft 19 extending through a supporting gear box 20 supported by the frame or cabinet and having a bevel gear 21 thereon meshing with a bevel gear 22 mounted on a horizontal shaft 23, which is connected to the motor 6 through suitable speed-reducing gears 24, 25.

The shaft 23 is normally disconnected from the motor shaft and is connectible thereto by a suitable clutch and as here illustrated and as will be presently described, the shaft is shiftable axially to engage and disengage the clutch.

The shaft 23 is journaled at one end in a bearing in the casing 5 of the washing machine mechanism in alinement with the shaft 27 on which the gear 24 is mounted, and at its other end in the gear box 20. This shaft 23 is shiftable axially relatively to the gear 22 thereon within the gear box 20 to carry a

pin 28 thereon into and out of the notch 29 on a collar rotatable with the shaft 27, by means of the suitable shifting lever 30 mounted on a rock shaft 31 which is provided with a handle preferably located at the top of the cabinet.

The wringer is mounted to swivel about the axis of the tubular extension 9 into a plurality of angular positions as indicated 10 in Fig. 2, and as here shown a lock or base plate 300 is provided at the base of the bracket 8 and near the top of the extension 9 and on which the wringer swivels, this plate being movable vertically with the 15 wringer and supporting bracket, and being arranged to swing into position to engage the upper edge of the cabinet when the wringer is in its uppermost position. The member 300 thus constitutes a means for holding the wringer assembly and the tube 9 in their upper operative position.

As here illustrated, the plate is formed with a hub 31 encircling the extension 9 at the base of the bracket 8 and with a flange 25 having spaced apart shoulders 32 which form a groove for receiving the upper edge of the cabinet to prevent side sway of the wringer assembly. The wringer is held in any angular position to which it is adjusted 30 by suitable means as pivoted locking dog 34 pivoted at 35 to the bracket and movable into notches provided in the hub 31 of the locking plate 300.

The compression means for the rolls of 35 the wringer may be of any suitable form, size and construction, and in so far as this invention is concerned, includes one or more levers 36 which project upwardly above the top of the wringer when the rolls are under 40 compression and also above the top of the cabinet, thereby preventing closing of lid or cover of the cabinet in case the wringer is lowered within the cabinet without releasing the compression on the rolls by moving 45 the levers 36 to their horizontal position. Hence, the operator cannot close the cover of the cabinet when the machine is to remain idle without first releasing the compression on the rolls. When the wringer is 50 lowered within the cabinet the base of the bracket 8 or the plate 300 rests upon the upper face of the fixed bracket 10* of the cabinet.

In operation, when it is desired to use the 55 wringer it is moved from the position shown in Fig. 1 to that in Fig. 3, and the plate 300 swung about its axis until it rests upon the upper edge of the cabinet 2, the shaft 16 which telescopes with the shaft 19 sliding 60 outwardly thereon during this operation.

By throwing the clutch lever 30, the shafts 19 and 16 will be actuated from the motor 6 and by manipulating the handle 18 either the gear 13 or 14 will be clutched to the

shaft 12 and thus rotate the rolls 11 and 11* 65 in one direction or the other.

By operating the dog 34, the wringer can be swiveled into any desired angular position.

This wringer arrangement for washing 70 machines is particularly advantageous in that when the machine is not in use, the wringer can be lowered within the cabinet and the cover placed on the cabinet.

The advantages of this arrangement are 75 obvious especially where the machine is kept in a kitchen or other room used for other purposes than as a laundry.

What we claim is:

1. In a wringer construction, the combination with a cabinet and a wringer mechanism movable to an operating position above the cabinet and to a stored position within the cabinet, of a source of power, power-transmitting means operatively connecting the source of power to the wringer comprising a vertical shaft within the cabinet consisting of two telescoping members, a tubular member surrounding the upper telescoping member, a fixed bracket secured 80 to the cabinet, means securing the wringer mechanism to the upper end of the tubular member and serving to support the wringer mechanism on the fixed bracket when the wringer mechanism is in its stored position 85 in the cabinet, and means secured to the upper end of the tubular member for operatively engaging the upper edge of the cabinet when the wringer mechanism is in its operative position to prevent side sway 90 thereof.

2. In a wringer construction, the combination with a cabinet and a wringer, of a vertical power shaft embodying extensible means for driving the wringer whereby the wringer may be moved vertically to a position above or below the top of the cabinet, a wringer-supporting bracket and a tubular depending extension therefor, a fixed bracket surrounding the lower end of the tubular extension when the wringer is in its upper position and means on said wringer-supporting bracket for operatively engaging the upper edge of the cabinet when the wringer is in its upper position to prevent side sway 110 thereof.

3. In a device of the character described, a cabinet, a wringer therein, a vertically adjustable support and extensible driving mechanism extending therethrough for supporting and driving said wringer, and a horizontal anchoring plate on the wringer support operatively engaging the cabinet, the plate and the cabinet cooperating to effect a multi-direction restraint against movement to hold the wringer rigidly in its operative position.

4. In a wringer construction, the combi-

nation with a cabinet, a wringer in the upper part of the cabinet and a motor in the lower part of the cabinet, of a vertical extensible drive shaft operatively connecting the wringer and the motor consisting of two telescoping members, a fixed bracket and a gear box mounted in the cabinet to support the respective members of the shaft, and a

driving connection from the motor to the drive shaft extending into the gear box. 10

In testimony whereof, we have hereunto signed our names at Syracuse, in the county of Onondaga, and State of New York, this 17th day of June, 1921.

JOHN J. DOSSERT.
EDWIN E. GREAVES.
